COMBINED AMPLIFIER, MICROPHONE COLUMN SPEAKERS HAVING A CARRYING CASE THEREFOR

Henry W. Shaw and Milton N. Lanford, Morrilton, Ark., assignors to Sound-Craft Systems, Inc., Morrilton, Ark.

Filed Mar. 7, 1969, Ser. No. 16,123

Term of patent 14 years

Int. Cl. D14—04; D17—99
U.S. Cl. D26—14

Fig. 1.

Fig. 2.

FIG. 1 is a front perspective view of a combined amplifier microphone column speakers having a case therefor, embodying our new design;

FIG. 2 is another perspective view of the apparatus of FIG. 1 and illustrating the storing and semiclosed condition of the carrying case and associated components.

The undisclosed rear portions of the combined amplifier unit are substantially plane and unornamented.

We claim:

The ornamental design of a combined amplifier, microphone column speakers having a carrying case therefor, substantially as shown and described.
